(57) **CLAIM**

The ornamental design for a case for recording media, as shown.

DESCRIPTION

FIG. 1 is a perspective view of a case for recording media showing our new design;

FIG. 2 is a front elevational view thereof;

FIG. 3 is a right side elevational view thereof;

FIG. 4 is a top plan view thereof;

FIG. 5 is an enlarged front elevational view thereof along the line 5-5 of FIG. 2;

FIG. 6 is an enlarged cross sectional view thereof along the line 6-6 of FIG. 5; and,

FIG. 7 is another enlarged cross sectional view thereof along the line 7-7 of FIG. 5.

Portions in broken lines are for illustrative purposes only and no part of the claimed design.

1 Claim, 6 Drawing Sheets
